UNITED STATES PATENT OFFICE

HARRY N. MATHEWS AND DUDLEY VAN HOLLAND, OF NEW YORK, N. Y.

MANIFOLDING-SHEET FOR TYPE-WRITING.

No. 806,818.

Specification of Letters Patent.

Patented Dec. 12, 1905.

Application filed March 12, 1904. Serial No 197,875.

To all whom it may concern:

Be it known that we, HARRY N. MATHEWS, a resident of the borough of Brooklyn, and DUDLEY VAN HOLLAND, a resident of the borough of Manhattan, city and State of New York, citizens of the United States, have invented certain new and useful Improvements in Manifolding-Sheets for Type-Writing, of which the following is a specification.

10 Our invention has for its object the provision of new and useful means for enabling one to produce an original and one or more carbon copies of a letter, bill, or other matter at a single operation, and is particularly 15 adapted for use in type-writing machines.

Heretofore the usual practice in taking carbon copies has been to take as many carbon sheets and plain sheets as the number of copies desired and to arrange them into a collection 20 of loose leaves wherein the carbon-sheets and plain sheets alternate. Such an arrangement, however, is objectionable in that considerable work is involved in placing the leaves together accurately, and the handling of the 25 carbon-sheets is disagreeable, as it soils the fingers. According to our invention each plain sheet, except the original, is joined to another sheet, the surface of which is thinly carbonized upon its inner surface, the carbon 30 surface being sufficient to produce one good copy. When the duplex sheet thus formed has been used, the carbon-sheet is detached and discarded. For the purpose of enabling our arrangement to be employed for producing 35 a greater number of carbon copies of successive operations we employ a number of loose plain sheets between the duplex sheet.

Reference is hereby made to the accompanying drawings, in which—

40 Figure 1 is an edge view of one form of our invention. Fig. 2 is a plan view of the duplex sheet of Fig. 1, the plain leaf being partly broken away to show the carbon-leaf which ordinarily lies above it. Fig. 3 is a broken 45 view of the central portion of the duplex sheet, showing the plain and carbon leaves opened out. Fig. 4 is an edge view of a slight modification of the duplex sheet of Fig. 1. Fig. 5 is a plan view similar to Fig. 2 of 50 the duplex sheet shown in Fig. 4. Fig. 6 is an edge view of a further modification of our invention, and Fig. 7 is a perspective view of the arrangement of Fig. 6 with a letter-head superimposed thereon to receive the original 55 impression.

The manifolding-sheet shown in Figs. 1, 2,

and 3 consists of a single sheet of paper folded at or near a central transverse line, forming two leaves 1 and 2. The leaf 1 is carbonized upon its inner surface, as shown, and leaf 2 60 is left plain to receive a carbon impression from the leaf 1. We also preferably, although not necessarily, provide a line of perforations 3 at or near the line of fold. The carbonized surface of leaf 1 is designed to 65 make but a single copy—namely, that upon the leaf 2—and for this reason may be very cheaply made.

In the form shown in Figs. 4 and 5 the leaves 1' and 2' are made of separate sheets 70 of paper secured together at 4 by a suitable cementing material, and a line of perforations 3 may also be provided.

In using either of the forms of manifolding-sheets just described the user selects a plain 75 sheet or letter-head to receive the original impression and as many of the duplex sheets as he desires carbon copies. These sheets may be very easily assembled and placed in the machine. Thus if an operator desires to make 80 one, two, three, or four carbon copies only two to five loose sheets would be handled—that is, the single sheet for the original copy and one or more duplex sheets—while as heretofore practiced the operator would handle 85 one sheet for the original copy plus one carbon-sheet and one plain sheet for every carbon copy desired, or, in other words, three to nine loose sheets. Considerable care is required to insert these sheets evenly in the 90 type-writer carriage and much time is lost. Upon removal from the type-writer the leaves 1 and 2 or 1' and 2' are torn apart along the weakened line, which may be either the perforations or the line of fold, and the carbon-leaves 1 and 1' may then be discarded. 95

In the form shown in Figs. 6 and 7 a duplex sheet similar to those of Figs. 1 and 4 is used. Between the leaves 1 and 2 a number of plain 100 loose sheets or leaves 5 are inserted of any convenient number, as ten, for instance. The carbon-surface of the leaf 1 should be capable of making ten separate impressions or as many impressions as there are loose sheets 5. When using the manifolding-sheets in that 105 way, a loose sheet or letter-head 6 is placed above leaf 1, as shown in Fig. 7, and the device is then inserted in the type-writing machine. A carbon copy of the matter written on the original sheet 6 will be made on the 110 first loose sheet 5—that is, the one next to the carbon-face 1. Upon removing the sheets

from the machine the original and the carbon copy are removed, and the manifolding-sheets are then ready for further use with another loose sheet or letter-head upon which to write the original and may be used until all the leaves 5 have been exhausted.

What we claim is—

As a new article of manufacture, a manifold-sheet for type-writing comprising a long sheet 10 of paper having a coating of carbon on one side covering the entire width and one-half the length of the sheet and folded where the carbon-surface ends so as to form a duplex sheet with the carbon-surface on the inner 15 side, and a number of plain sheets placed between the parts of said duplex sheet and the whole designed to be inserted in a type-writ-

ing machine with a letter-head or the like in front thereof and which receives the impressions from the type of the machine and which 20 impressions are duplicated on the first plain sheet adjacent to the carbon-surface of the duplex sheet, and said duplex sheet with its pack of plain sheets may be used again with another letter-head or the like after removing 25 the carbon copy previously made.

This specification signed and witnessed this 7th day of March, 1904.

HARRY N. MATHEWS.
DUDLEY VAN HOLLAND.
